UNITED STATES PATENT OFFICE.

SAMUEL HANCE LEWIS, OF PRINCETON, WEST VIRGINIA.

CYLINDER CONSTRUCTION.

1,074,056.

Specification of Letters Patent. Patented Sept. 23, 1913.

Application filed December 14, 1912. Serial No. 736,837.

To all whom it may concern:

Be it known that I, SAMUEL H. LEWIS, a citizen of the United States, residing at Princeton, in the county of Mercer and State of West Virginia, have invented certain new and useful Improvements in Cylinder Construction, of which the following is a specification.

My invention relates to new and useful improvements in railway locomotives and has particular reference to the cylinder construction thereof and the means and manner of attaching the same to the locomotive saddle and frame extension or slab associated therewith.

An important object of this invention is to provide means of the above mentioned character, whereby the efficiency of the engine or locomotive will be increased by affording the shortest direct passage for the exhaust and the live steam, the lowermost portion of such passages being disposed above the slab or frame connected with the saddle and being free from intersection therewith, whereby it is possible to secure satisfactory steam-tight connection between the cylinder casting and saddle.

A further object of my invention is to provide means of the above mentioned character, which are strong, simple in construction, and durable.

Other objects and advantages of the invention will be apparent during the course of the following description.

In the accompanying drawings forming a part of this application and in which like numerals are employed to designate like parts throughout the same, Figure 1 is a front view of the locomotive showing the saddle and the steam-chest and cylinder connected, therewith, a part of the saddle and the corresponding steam-chest and cylinder being broken away. Fig. 2 is an inner side view of the steam-chest and cylinder casting, the same being removed. Fig. 3 is a horizontal sectional view taken on line 3--3 of Fig. 1 and looking downwardly as indicated by the arrow. Fig. 4 is a vertical sectional view taken on line 4--4 of Fig. 1. Fig. 5 is a front end view of the locomotive, the steam-chest and cylinder and associated elements being shown in vertical section, and, Fig. 6 is a side view of the saddle, the steam-chest and cylinder being removed.

In the drawings, wherein for the purpose of illustration, I have shown a preferred

embodiment of my invention, the numeral 7 designates the engine or locomotive boiler, the forward end of which is mounted upon a saddle 8, as shown. The saddle 8 is cast with suitable openings to reduce its weight. As clearly shown in Fig. 6, the saddle 8 has each side thereof in the form of a flat plate 9, the upper and lower portions of which lie in different vertical planes, to form a shoulder 10. The edges of the plate 9 extend beyond the saddle 8, as shown.

The numeral 11 designates a cylinder casting or construction, including a steam-chest 12 and a cylinder 13, which are arranged in the ordinary superposed horizontal relation. This casting further comprises an inner flat plate 14, the upper and lower portions of which lie in different vertical planes, for providing a shoulder 15. The casting 11 may be formed with suitable openings to reduce its weight. The flat plate 14 has its edges extending beyond the casting 11 proper and is co-extensive with the co-extensive flat plate 9. Disposed between the flat plates 9 and 14, below and in engagement with the shoulders 10 and 15, is the ordinary slab or frame 16. The lower portions of the flat plates 9 and 14 are connected by bolts 17 or the like, which pass through the slab or frame 16. The upper portions of the plates 9 and 14 are connected by bolts 18, as shown.

Formed through the upper portion of the casting 11 are substantially horizontal exhaust ports 19, which lead into the opposite ends of the steam-chest 12, as more clearly shown in Fig. 3. These exhaust ports 19 converge inwardly and pass through the upper portion of the flat plate 14. The exhaust ports 19 are in registration with exhaust ports 20, formed in the upper portion of the saddle 8. The outer portions of these exhaust ports 20 are horizontal and pass through the upper portion of the flat plate 9, as shown. The exhaust ports 20 converge inwardly and meet or discharge into a common upwardly curved exhaust port 21, which discharges below the smoke stack, as is customary. Attention is called to the fact that exhaust ports 19 pass through the periphery or inner side of the steam-chest 12, at or adjacent heads 12^a, which close the ends of the steam-chest. By this construction the exhaust ports have connection with the steam-chest without the employment of additional couplings or the like between the exhaust port and the heads

12^a. It is seen that my construction is simple and cheap to manufacture. It is thus seen that the portions of the exhaust ports which are adjacent the slab or frame 16 are arranged above or to one side of the slab or frame 16, whereby the exhaust ports have no intersection with the slab or frame 16. The advantage in doing this is to avoid having these exhaust ports cut or passed through the slab or frame. It has been found when the exhaust ports do cut or pass through the slab or frame 16 that it is exceedingly difficult if not impossible to obtain a steam-tight connection between the ports at that point. By arranging the exhaust ports 19 above the slab or frame 16, the length of the exhaust ports is decreased and the shortest possible direct exhaust passages are provided for the steam passing from the steam-chest, which greatly increases the efficiency of the engine. Suitable packing (not shown) may be interposed between the upper portions of the flat plates 9 and 14 adjacent the exhaust openings.

25. Mounted to reciprocate within the steam-chest 12 is a valve 22, comprising a reduced central portion or spindle carrying at its ends enlarged heads 23. This valve is of the ordinary construction and is shifted by a rod 24, connected with the valve gear (not shown) as is customary. It is obvious that the valve 22 is adapted to cover and uncover the exhaust ports 19.

Connected with the boiler 7 is a live steam supply pipe 25, connected with a live steam supply pipe 26, through the medium of a suitable coupling 27. The pipe 26 is preferably cast integral with the steam chest 12 and leads into the upper side of the same midway between the ends thereof, as more clearly shown in Fig. 4.

The numeral 28 designates ports, serving to establish communication between the steam chest 12 and cylinder 13, as shown. These ports alternately serve as inlet and exhaust ports. The ports 28 leading to the ends of the cylinder 13 upon opposite sides of a piston 29, have connection with a piston rod 30. The piston rod 30 is connected 50 with the driving wheels, in the ordinary manner. When the valve 22 is in the forward position, as shown in Fig. 4, steam in the right end of the cylinder 13 is being exhausted and live steam is being fed into the left end of the cylinder to move the piston 29 to the right. When the piston 29 has reached the end of its travel to the right, the valve 22 is shifted to the right, whereby

the steam in the left end of the cylinder is exhausted and live steam is fed into the right end of the cylinder to move the piston to the left.

By my construction, it is possible to directly connect the exhaust ports 19 and 20 (the adjacent portions of the same being above the slab or frame 16 and not passing therethrough) so that a perfect steam-tight joint is obtained. These exhaust ports form the shortest possible direct passage for the exhaust of the steam to the atmosphere, below or adjacent the smoke stack. The curved common exhaust port 21 offers the least possible resistance to the exhaust. In this manner the back pressure upon the piston in the cylinder is reduced, with a corresponding increase of power or efficiency of the engine. Attention is called to the fact that the exhaust ports in the casting 11 are directly connected with the exhaust ports in the saddle without interference with the slab or extension frame 16 and without the use of a connecting pipe or gland which has been found to be economical. By my construction it is possible to quickly and easily remove the steam-chest and cylinder from the saddle, the same being connected therewith by a single joint.

It is to be understood that the form of my invention, herewith shown and described, is to be taken as a preferred example of the same, and that certain changes in the shape, size and arrangement of parts may be resorted to without departing from the spirit of the invention or the scope of the subjoined claim.

Having fully described my invention, I claim:—

The combination with a frame extension, of a separate saddle disposed upon the inner side of the frame extension, a steam-chest-cylinder casting disposed upon the outer side of the frame extension and having exhaust ports leading into the opposite ends of the steam chest and crossing the frame extension at a point spaced from the same, so that it does not intersect therewith, means connecting the saddle and steam-chest-cylinder casting with the frame extension, and means to supply live steam to the steam chest.

In testimony whereof, I affix my signature in presence of two witnesses.

SAMUEL HANCE LEWIS.
